UNITED STATES PATENT OFFICE.

WILLIAM THOMAS, OF BEATRICE, NEBRASKA, ASSIGNOR TO DEMPSTER MILL MANUFACTURING COMPANY, OF BEATRICE, NEBRASKA, A CORPORATION OF NEBRASKA.

TWIN-PUMP UNIT.

Application filed March 10, 1924. Serial No. 698,195.

This invention particularly relates to pumping units and involves a multi-cylinder assembly and pump coupling and operating means, and the purposes and objects of the invention will be readily understood by those skilled in the art in the light of the following descriptions of the accompanying drawings illustrating what I now believe to be the preferred mechanical expression or embodiment of the invention from among other constructions and arrangements within the spirit and scope thereof.

An object of the invention is to provide various improvements with the end in view of producing a compact, comparatively simple, and efficient twin pump unit that will be economical in production and upkeep and easy in operation and adjustment.

With these and other objects in view my invention consists in certain novel features in construction and in arrangements and combinations as more fully and particularly set forth and specified hereinafter.

Referring to the accompanying drawings forming a part hereof:

Fig. 1 shows a pumping unit embodying my invention, in side elevation, parts being broken away, and the base pan being shown in vertical longitudinal section.

Fig. 2 is a detail top plan view of the base pan.

Fig. 3 shows the pumping unit of Fig. 1, in top plan, certain parts being broken away.

Fig. 4 is an end view of the unit, certain parts being broken away, the base pan being shown in vertical cross section.

Fig. 5 is a detail edge view of the frame mounted on the outer end of the left hand pump cylinder (Figs. 3 and 4) for carrying the power driven gearing for actuating the twin pumps.

Fig. 6 shows said frame in vertical section.

Fig. 7 is a detail top plan of the main cross head or slide for operating the twin pumps, certain parts being partially broken away, portions of the guide-forming tie rods being shown, the coupling head of one pump piston rod being shown operatively coupled to the cross head, the coupling head of the other pump piston rod being shown opera-

tively disconnected from the cross head, the hand lever socket not being shown.

Fig. 8 is a side elevation of the structure and arrangement of Fig. 7.

Fig. 9 is a detail cross section on the line 9—9, Fig. 7.

Fig. 10 is a detail cross section on the line 10—10, Fig. 7.

In the particular embodiment shown for purposes of explanation, I provide two similar pumps A, B, and common pump operating means, the pumps being of the reciprocating double-acting type. However, I do wish to so limit my invention for among other variations that might be adopted, pumps of the single acting type can be employed if so desired.

Each pump, whether single or double acting embodies a horizontally arranged cylinder 1 that contains a suitable reciprocating plunger or piston (not shown) operated by reciprocating horizontal piston or plunger rod 2. Each pump or its cylinder is provided with rigid depending supporting legs, or with a depending pedestal 3, rigid therewith and having rigid bottom feet 3', usually arranged at the ends thereof to provide four corner feet 3', although I do not wish to so limit my invention.

These two cylinders are mounted and assembled in fixed relation, as a unit, with the two cylinders spaced apart and arranged in juxtaposition in longitudinal alinement with their two piston rods 2, preferably in longitudinal alinement. The two pumps are horizontally arranged in juxtaposition and in opposed relation, in that their rear ends are at the outer ends of the unit and their front or inner ends are opposite or facing each other intermediate the unit with the piston rods 2 projecting toward each other in the space between the cylinders and from the facing or opposing inner ends of the cylinders.

The unit carries or includes pump operating means that is detachably coupled to both piston rods 2 for simultaneously operating both pumps, and such operating means is capable of detachment from either piston rod so that either pump can be operated without

the other. The two individually complete pumps are assembled to constitute a portable pumping unit, by being secured in fixed relation to a common base member and by being rigidly braced and tied together by means arranged above the base member and extending longitudinally between and connecting the two pump cylinders.

In the particular example illustrated, the base or bed member is formed by and composed of a single one-piece strong rigid flat horizontal longitudinally-elongated metal plate or casting 4 in the form of an open-top pan by the provision of an encircling or continuous upstanding edge flange 4', and preferably by the provision of an upstanding transverse top flange 4'', midway the length of the bed and forming a dam or division wall sub-dividing the pan into two preferably non-communicating halves, although I do not wish to so limit all features of my invention. The formation of the bed plate, as a pan, renders the bed exceedingly stiff and strong with relation to weight of metal employed.

If so desired, the flange or rim 4' can be formed with lateral enlargements having vertical holes 4^a, for the passage of bolts or other fastening means by which the bed can be secured to a floor or other support, without danger of leakage of liquid from the pan through such holes. The pumps are so secured to this bed that both pumps are over the pan in such manner that the pan will catch and retain all leakage and drippings from the pumps.

In the particular example illustrated, one pump is fixed to and arranged over one end portion of the bed and the other pump is fixed to and arranged over the other end portion of the bed so that the separate halves or sub-divisions of the pan catch and retain the drippings from the pumps, respectively.

In this example, the end portions of the bed are formed with upstanding lugs or bosses 4^b, located within the pan, to receive the feet 3', of the pump cylinders, and these bosses are vertically bored or otherwise formed for the passage of bolts 5 or the like by which said feet are tightly clamped down on the bosses and held elevated above the floor of the pan. The pump cylinders are thus rigidly secured to the bed and held in fixed relation and in the desired elevated positions, and the two cylinders are braced and stiffened in this fixed relation by a direct stiff longitudinal connection horizontally bridging the space between the two cylinders and elevated above and usually parallel with the bed 4.

For instance, in the example shown, the cylinders are braced and tied together by a pair of straight parallel stiff spaced rods 6, extending longitudinally from one cylinder to the other and at their ends fixed to the in-

ner or facing end plates or heads 1^a, of the cylinders. For instance, the end heads 1^a, are cast with horizontal sockets 1^b, at the outer faces of the heads, the ends of the rods 6, fitting and secured in the sockets as by clamping screws 1^c. In the example shown, these tie and brace rods 6 are arranged in a common horizontal plane located below the horizontal plane in which the piston rods 2, are located, and the vertical plane in which the two piston rods are located is arranged midway between the vertical planes in which the two rods 6 are located although I do not wish to so limit my invention.

In the example illustrated, these bracing tie rods 6 are utilized to form the support and guide for a sliding or reciprocating cross head through the medium of which the pumps are operated.

In the particular embodiment shown, this cross head is composed of a one-piece frame or casting that rises from the two guide rods and bridges the space between the same, and is formed with bottom sleeves 7 that longitudinally receive and slide on said guide rods. These sleeves are arranged longitudinally of the opposite side portions of the cross head.

The opposite ends of the cross head that face the pump cylinders, respectively, are similar or alike in structure or formation, and are adapted to have the piston rods 2, secured thereto in such manner that the cross head will form the connecting member between the piston rods and will be located midway between the two pump pistons. Power applied to the cross head to reciprocate the same on and longitudinally of the guide rods will hence reciprocate the pump pistons and operate the pumps.

Various means and formations can be provided for thus coupling together the cross head and piston rods. For instance, I provide the free end of each piston rod with a coupling cross member or head 9, in the form of a metal block. Each coupling head 9, is formed with a rear socket or hub 9', located midway between its ends to receive the rear or inner end of its piston rod 2, and the coupling head and piston rod are normally operatively fixed together in any suitable manner, as by clamping screws 9^a.

The free or front longitudinal face 9^b of each coupling head 9 faces and is parallel with the adjacent end of the cross head, and is formed to squarely abut the said adjacent cross head end and be clamped tightly thereagainst. For instance, in this example, the coupling heads 9 are formed with flat faces 9^b, to squarely abut and fit corresponding parallel flat end faces 7^b of the cross head, although I do not wish to so limit all features of my invention. Various means can be provided for normally, yet detach-

bly, fixing together the cross head and the two coupling heads 9, in such manner that said coupling heads are independently or separately attachable to and detachable from the cross head. While I show clamping bolts 10, for this purpose, yet I do not wish to so limit my invention. In the particular example illustrated, four bolts 10 are provided, a pair for each coupling head, with the bolts arranged parallel with the path of movement of the cross head and located at both ends of each coupling head and directly clamping the coupling heads and cross head together with their transverse flat faces 7^b, 9^b, squarely abutting. In the example illustrated, each coupling head is approximately bifurcated at both ends, to form open-side bolt holes or sockets 9^c, for the bolts 10, while the rear faces of the end portions of the coupling head form seats for the washers or nuts 10', of the bolts.

In the particular example shown, each end of the cross head, at opposite sides thereof, is formed with open-side sockets 7^c, to receive the heads and shanks of two bolts 10 and anchor the same therein against longitudinal movement.

Each piston rod coupling head is thus independently secured to the cross head and can be uncoupled from or coupled to the cross head without disturbing the other coupling head. In this instance, each coupling head is at both ends tied to and rigidly against the cross head by the end clamping bolts, and the bolts can be removed laterally from the coupling head and cross head to uncouple the parts after the bolt nuts have been loosened without entirely removing such nuts from their bolts, and can be as easily applied and then tightened up to couple the parts together.

In the example illustrated, I show the actuating power applied to the cross head midway its length, through the medium of a cross shaft or pin 11 extending therethrough and at both ends projecting in opposite directions beyond the opposite sides of the cross head. This cross pin 11, is transversely arranged with respect to, and is located above, the guide rods 6 and the sleeves 7, and extends through elevated transverse alined hubs or sleeves 7' of the cross head midway between the opposite ends of said head. This cross pin is preferably endwise removable from the cross head, although I do not wish to so limit all features of my invention, and means are preferably provided whereby manual power can be applied to said cross pin to actuate the cross head, or whereby motor or other power can be applied to actuate the cross head.

Various means can be provided for manually actuating the cross head, although in this instance, I show an upright lever 12, for this purpose, adapted to be manually swung

back and forth and through the pin 11 to thus reciprocate the cross head. The pin 11 extends loosely through this lever at a point above the lever fulcrum. The lever is fulcrumed at 12', by a cross pin or pivot to the otherwise free end of a vertically swingable fulcrum link or frame 13, at its opposite end pivoted or hinged through pivot or pin 13', to the pedestal or leg of one of the pump cylinders. The hand or manual lever preferably includes an open-upper-end upright metal socket end 12^a, that forms the lower end of the lever and that removably receives the main length of the lever. The cross head is formed with a central vertical intermediate opening 8, through which the socket 12^a, vertically extends, and this opening is centrally bridged by the cross pin 11, which pin loosely and removably extends transversely through the socket, the socket being provided with a transverse bearing opening for the purpose.

When the lever is not in use to actuate the cross head, the lever section 12 can be removed from the socket. When other power than the lever is being employed to actuate the pumping unit, the metal socket 12^a, can remain and will then merely idle back and forth with the cross head, or said socket can be lifted from the cross head, the pins 12', 11, being first removed.

The pumping unit is preferably, also equipped with a power driven pump jack for operating the cross head, and this jack can be operatively coupled to and disconnected from the cross pin 11, of the cross head.

The power jack is mounted on and carried by the rear end of one of the pump cylinders, for instance, the cylinder of the pump A, and the jack comprises a horizontal transverse main or drive shaft 15 which can be coupled to and driven from any suitable source of power by any suitable means or in any suitable manner. This shaft carries and drives pinions 16, that mesh with and drive gears 17 carried by countershaft 18, and the gears 17 are provided with crank or wrist pins 19, that actuate pitmen 20. The opposite or inner ends of the pitmen 20 are formed with transverse end sleeves 20^a, 115 removably fitted on the projecting ends of the cross pin 11, and removably confined thereon by cotter pins 11^a, or in any other suitable manner.

The pitmen are also preferably removably confined on the crank pins 19, by cotter pins 19', or other suitable means.

The two pitmen 20, extend from the crank wheels 17 forwardly at opposite sides of the pump A, and at their front or inner ends couple to the opposite ends of cross pin 11.

The power jack can be operatively disconnected from the cross head by removing the cotter pins from the crank pins 19 and from the cross pin 11, and then slipping

the pitmen from such pins, or by slipping the cross pin 11 endwise from the cross head and pitmen to release the pitmen, and then reinserting the cross pin in the cross head 5 and lever socket 12.

The power jack is carried by a vertical frame or plate 21 that forms or includes the rear end head or plate of one of the pump cylinders. This plate or frame provides an 10 elongated transverse top journal box 21^a, (having a vertically removable top cap) for the main shaft 15 with the pinions 16 located beyond the opposite ends of the box and side edges of the frame. The plate 21, 15 at the proper distance below the main shaft, provides a transverse journal box 21^b, for the countershaft 18 with the large crank wheels or gears 17 beyond the side edges of the plate and beyond the opposite sides of 20 the rear end of the pump cylinder. The journal box 21^b, is provided with a rearwardly or outwardly removable cap at the rear side of the plate.

The plate 21 is constructed and arranged 25 to carry the gear or jack assembly so that the assembly, as a unit, can be thus applied to and removed from the rear end of the pump cylinder by the usual fastenings that secure the rear plate or head to the cylinder. 30 The front side of the plate is formed to fit the rear end of the pump cylinder when the plate is secured thereto by suitable bolts.

The plate is so formed and arranged that 35 the axis of the crank or gear wheels 17 will be in the same horizontal plane as the cross head cross pin 11, and the cross head is so arranged that said cross pin is in the same horizontal plane as the two piston rods 2, although I do not now wish to so limit all 40 features of my invention.

Advantages are gained by securing the 45 two pumps on a common base constituting a rigid connecting frame between the pumps while the frame or unit, as an entirety, is stiffened and braced by the elevated rigid connection formed by the guide rods 6 between the cylinders which counteract any 50 tendency of the pump cylinders to rock or tilt forwardly or backwardly on the bed when subjected to heavy load under the power of the reciprocating pistons. The bed and the guide rods cooperate in the formation 55 of a stiff rigid framework, the ends of such framework being the pump cylinders, the lower longitudinal side of the framework being formed by the common bed and the upper longitudinal side being formed by the guide rods 6.

A further advantage is gained by securing 60 the two pumps on a common bed that forms a pan to catch the drippings from the cylinders, whether or not such pan provides a separate receptacle for each cylinder, as the floor in the vicinity of the pumping unit can 65 be thereby kept clean, and liquid leaking

from the pumps can be thereby reclaimed by drainage pipe connections from such receptacles. The fire hazard is thereby reduced, and waste avoided, and these features are of particular moment where such fluids 70 as kerosene and gasoline are being handled by the pumps.

A pumping unit in accordance with my invention reduces to the minimum, strain on foundation bolts, reduces the area of floor 75 space required, reduces cost of production and the number of parts required, and also reduces cost of upkeep, as compared with separate pump arrangements even where common operating means is provided for 80 such separated pumps.

I also gain advantages by the intermediate cross head for operating both or either pump where each pump piston rod is equipped with a coupling head for quickly 85 and easily coupling to and detaching from such cross head, particularly where the relative formations are such that when a coupling head is detached, the reciprocation of the cross head will act automatically to push 90 the detached coupling head back out of the way without danger of becoming accidentally entangled therewith or attached thereto or caught thereon. Advantages are also gained by the ease and rapidity of attaching 95 and detaching the coupling heads from the cross head.

Advantages are also gained by the exceedingly simple quickly operated connections between the pump piston rods and the intermediate pump actuating cross head through which both pumps can be as effectively operated together or simultaneously, as can either pump be operated while the other pump remains at rest, and that without changing or disturbing the driving or actuating mechanism or gearing coupled to the cross head for the reciprocation thereof. The pumping unit of this invention is well adapted to situations where different liquids 100 (such as kerosene and gasoline) are to be moved through separate pipe lines, as the two pumps of the unit can be coupled into such lines, respectively, and both pump pistons can be coupled to the cross head where 105 it is desired to move both liquids simultaneously, or one or the other of the pumps can be coupled to the cross head and the other disconnected therefrom, (simply by loosening and slipping bolts 10 in or out and again tightening the same) as one or the other liquid requires moving. By coupling both pumps of the unit into the same pipe line and attaching both pump pistons to the cross head, the full pumping capacity of the 110 twin pumps of the unit can be utilized.

Advantage is also gained in the arrangements whereby the power is applied to the cross head in the direction of movement of that head and in a manner to avoid lateral 115

thrust or disturbance of the longitudinal alignment of the pump parts and cross head.

It is evident that various changes, modifications and variations might be resorted to, that features might be added, and parts omitted, all without departing from the spirit and scope of my invention, and hence I do not wish to limit myself to the exact disclosures hereof.

10 What I claim is:—

1. A pumping unit comprising a pair of spaced opposed reciprocating pump cylinders secured in fixed relation with their reciprocating piston rods extending into the 15 space between the cylinders, a reciprocatory cross head between said piston rods for reciprocating the same, an upright plate secured at the rear end of one of the cylinders, a transverse driven shaft carried by said 20 plate and having end cranks, and pitmen operated by said cranks and coupled to the cross head at opposite sides thereof to reciprocate the same.

2. In combination, a pair of cylinders 25 having reciprocatory pistons with their piston rods, fixed spacing and guide means connecting said cylinders, one slide carried by and reciprocatory along said means and located between and common to both piston 30 rods, attachable and detachable coupling means for said piston rods, respectively, for separately operatively coupling the same to and detaching the same from said one slide, a longitudinally removable cross pin extending 35 through said slide intermediate the length thereof with its ends projecting therefrom, and driving means removably and operatively applied to said slide through the medium of said pin for reciprocating said slide.

3. A pair of opposed spaced cylinders having their reciprocating piston rods extending into the space between cylinders and each at its inner end provided with a coupling head, a cross head interposed between 45 said piston rod coupling heads for reciprocating either or both of said piston rods to operate either or both cylinders, and operating means for reciprocating said cross head, said cross head having opposite end faces and said coupling heads having opposing faces to abut said cross head faces, exposed 50 accessible quickly attachable and detachable means being provided to independently and fixedly clamp said coupling heads to the opposite ends of said cross head with said faces abutting.

4. A pumping unit comprising two individually-complete separate horizontal plunger pumps mounted in fixed relation and opposition on one base, fixed guides connecting the two pumps, a cross head mounted between the two pumps on said guides, and accessible exposed quick action detachable 60 clamping means whereby said cross head

may be connected to or disconnected from the plunger rods of either one or both pumps.

5. The combination of two horizontal plunger cylinders spaced apart, a plunger 70 rod for each cylinder having a coupling head with an open aperture on each side to receive bolts, a cross head having open apertures on each side to receive bolts for securing it to the plunger rod coupling heads, exposed accessible laterally removable clamping bolts adapted to said apertures for quickly clamping or releasing either of both coupling heads to or from the cross 75 head, and means for reciprocating said cross head.

6. A pumping unit comprising two horizontal double acting plunger pumps spaced apart on one base, a driving mechanism mounted on one of said pumps, one cross head operatively connected with said driving mechanism, a plunger rod for each pump, and exposed accessible quick action 80 clamping and releasing devices for said rods, respectively, whereby either one or both of said plunger rods may be quickly and securely connected to said cross head.

7. In combination, two spaced horizontal plunger cylinders, means connecting said cylinders, one cross head slidable longitudinally of said means for reciprocating with the piston rods of the cylinders, the piston rods having end coupling heads between which the cross head is located, the cross head ends and the coupling heads 90 having corresponding faces that are formed to abut, and opposite side accessible exposed quick action laterally removable and applied clamping bolts for said coupling heads, respectively, for separately clamping the coupling heads against the cross head, whereby the coupling heads can be independently released from or clamped to the cross head.

8. In combination, two spaced horizontal plunger pumps having their reciprocating piston rods extending into the space between the pumps and pump operating means embodying a reciprocatory cross head interposed between said piston rods, means for 100 separately attaching the piston rods to said cross head and for separately detaching the same therefrom whereby both pumps can be operated together or either pump can be operated while the other remains at rest, a central cross pin extending transversely of said cross head and at both ends projecting therefrom for the connection of operating pitmen thereto.

9. In combination, a pair of operatively aligned opposing separate fixed cylinders each having a reciprocating piston and its piston rod, the two opposing cylinders being spaced apart, a common bed plate to which 105 said cylinders are secured, fixed spacing and 110

- stiffening means secured to both cylinders above said bed to cooperate with said bed in maintaining said cylinders in fixed relation, the piston rods of the cylinders arranged between said means and extending into the space between the cylinders, means for operating said pumps embodying a single driven reciprocating member arranged between and common to both rods and slidably on said spacing means, and accessible exposed quick attachment and detachment coupling means for operatively connecting both rods to said reciprocating member and for operatively disconnecting either rod therefrom.
10. In combination, a pair of opposed individually complete reciprocating pumps constructed and arranged for coupling into separate pipe lines, respectively, one for driving a liquid such as oil and the other for driving a liquid such as gasoline; each pump embodying a fixed cylinder and a reciprocating piston and its piston rod, said opposing cylinders being spaced apart with the piston rods extending into the space between the cylinders, an exposed accessible actuating member arranged between and common to both piston rods, driving means for reciprocating said member, exposed accessible manually released and applied clamping devices between said member and said rods for operatively-fixing either or both rods to said member and for operatively releasing either or both rods therefrom, whereby either pump can be thrown out of operation or both pumps can be operated simultaneously, and means for maintaining said cylinders in rigid fixed relation embodying fixed supporting guide rods for said member and a bed plate common to both pumps and providing separate drip receptacles for the different liquid waste from the pumps.
11. In combination, a pair of opposed individually complete reciprocating pumps constructed and arranged for coupling into separate pipe lines, respectively, one for driving a liquid such as oil and the other for driving a liquid such as gasoline; each pump embodying a fixed cylinder and a reciprocating piston and its piston rod, said opposing cylinders being spaced apart with the piston rods extending into the space between the cylinders, a single reciprocating exposed accessible actuating member arranged between and common to both piston rods, exposed accessible manually released and applied clamping devices between said member and said rods, respectively, for operatively-fixing either or both rods to said member and for operatively releasing either or both rods therefrom, and means constituting a supporting slideway for said actuating member and for maintaining said cylinders in rigid fixed relation.
12. In combination, a pair of opposed individually complete fixed cylinders each having a reciprocating piston and its piston rod, said opposing cylinders being spaced apart with the piston rods extending into the space between the cylinders, a single piston rod reciprocating members arranged between and common to both piston rods, driving means for reciprocating said one member, exposed accessible manually released and applied clamping devices between said member and said rods, respectively, for operatively-fixing either or both rods to said member and for operatively releasing either or both rods therefrom, and means for maintaining said cylinders in rigid fixed relation embodying a bed plate common to both pumps and fixed guide rods for said one member.
13. In combination, a base plate, two individually complete pumps having horizontal pump cylinders secured on said plate in fixed aligned opposed relation with their reciprocating piston rods extending toward each other, fixed spaced parallel guide rods connecting said cylinders, pump operating means common to both piston rods for operating both or either pump, and embodying a single reciprocating member on said rods, and exposed accessible quickly applied and released devices for separately and detachably coupling said two rods to said one reciprocating member, whereby either or both rods can be operatively disconnected from and connected to the pump operating means.
14. In combination, a pair of opposed individually complete reciprocating pumps secured in fixed relation, operating means common to said pumps and embodying a single driven reciprocating cross head arranged between the pumps and movable toward and from the same and interposed between the piston rods of said pumps, and separate readily accessible manually applied and released quick-action means for independently and separately clamping said piston rods directly against and to the single cross head and for independently and separately detaching the same therefrom.
- Signed at Beatrice, in the county of Gage, and State of Nebraska, this 6th day of March, 1924.
- WILLIAM THOMAS.
